UNITED STATES PATENT OFFICE

1,976,117

MAIL BOX AND INDICATOR

James A. Cassel, Seattle, Wash.

Application April 20, 1931, Serial No. 531,415

1 Claim. (Cl. 177—311)

This invention relates to mail boxes and signals operated thereby.

The objects of this invention are to provide a mail box, or mail chute for receiving mail, with visual and audible signals to be electrically operated for disclosing to the owner thereof when mail has been deposited therein and when removed therefrom and for disclosing the kind of mail.

10 A further object is to provide a receiving mail box or chute to be built into the outer wall of a private residence or apartment house; the box having an upper and lower compartment, with the name or number of the house or owner 15 illuminated in the front of the upper compartment, and an outer door in the front of the lower compartment for receiving mail, with means operated by the door for sounding a series of alarms, the number thereof depending 20 on the size of the mail packages. The opening of a door also causing a light signal to shine until a lower door is opened for removal of the mail. Both signals to be given at any suitable location as at a distance from the box.

25 With these and other objects as will hereinafter appear, I have illustrated my invention by the accompanying drawings, of which:

Figure 1 represents a front elevation, Figure 2 represents a rear elevation with the back 30 covers removed. Figure 3 is a vertical section taken on lines 3—3 of Figure 2, Figure 4 is a vertical section taken on lines 4—4 of Figure 2, Figure 5 is a top plan in section, Figure 6 is a fragmentary enlarged view of a part of Figure 35 2. And Figure 7 is a diagrammatic view of the wiring.

Like numerals on the different figures represent like parts.

Numeral 8 shows the front wall, preferably 40 a metal casting of the upper compartment, with a transparent plate 9 over an opening under the plate, with opaque numerals 11 thereon to indicate the street number of the house, or apartment number, according to the situation of 45 the box. A light bulb 12 is positioned behind the numerals in a concave reflector 13, and is provided with electric circuit wires 14 and 15, with a switch 16 for manually cutting the current on and off as desired. The current is 50 taken directly from an ordinary transformer 17, which in turn receives a higher voltage from the ordinary house lighting wires 18 and 19.

55 20 represents the lower compartment of the box, or mail chute, into which the carrier deposits the mail for the box owner. The wall

8 extends down over a part of the chute, and is provided with a door 21, suspended on hinges 22, preferably from the top side, to swing inward a sufficient space for the various kinds of mail to pass, and ordinarily such space or distance varies from a slight degree for a letter to greater degree for a newspaper roll, and still greater for a Christmas package.

In order that the owner may be advised of the mail deposit, and the kind thereof, at any 60 suitable place in the house where an alarm is most likely to be heard, I provide a signal bell 23 of the ordinary type, in such place. The bell is connected with circuit wire 24 through the transformer 17 to a terminal 26 and return wire 65 25 to terminal 27 in an insulated block 28. I connect these by a resilient metal strap 29, the outer end of which is affixed to the block and the lower end normally rests below the terminals, but when pressed upward it unites the two terminals and completes the electric circuit, whereby the bell is caused to ring so long as the strap remains in such raised position. In order to raise the strap by the opening of the door, I attach thereto, in line with the hinges a lug 30, 70 a part whereof is provided with a series of insulated actuating teeth 31, with spaces 32 between, and on a radius corresponding with the movement of the door at that point. When the door is closed the free end of the strap 75 rests down in one of the spaces. But as the door is opened the teeth successively raise the strap and close the circuit. The bell is thus caused to ring as each tooth is rolled beneath the strap, as the door is opened or closed. The 80 owner soon learns the usual number of rings caused by a letter and larger package.

However as the owner may not be within hearing of the bell, or unable to hear the same for various reasons, it is important that a visual 95 signal be combined to further indicate the deposit of mail, and to continue so to do at a distance from the box till the mail is removed. This is specially important in modern apartment buildings where the owner may reside several floors above the location of the mail box.

100 For this purpose I provide a signal light bulb 33, preferably colored and located in the apartment where most likely to be observed. This bulb is connected with a circuit wire through 105 the transformer 17, to a fixed insulated contact point 35, and return wire 36 to a movable contact point 37, so that when these contact points are brought together, an electric circuit is formed and the bulb 33 caused to shine and continues to 110

so shine until the points are separated. The movable point 37 is preferably mounted by insulation on a sliding pin 38 and normally compressed apart from the point 35 by a spring 39, and preferably mounted in the upper compartment, above the floor 40 thereof, to be free from interference or injury by the deposited mail. The outer end of the pin 38 has a bevel and in order to compress the bolt and the point 37, inward to close the circuit, I provide a perpendicular square rod 41 slidably mounted through the floor 40 and a rib 8' on the wall 8, and is normally pulled downward by a spring 42. The top of the rod is beveled, and when the rod is raised this bevel operates against the bevel on the pin, and thereby the pin is pressed inward till the point 37 contacts with the point 35, to close the circuit.

On the door lug 30 I provide a curved eccentric bearing face 31' on which the lower end of the rod 41 freely rides when the door is opened. The inner position of this face is eccentrically formed, whereby the rod is forced to rise as the door opens, until the pin has been compressed and the circuit closed as described. The remainder of the curved face conforms to the radius of the door movement, so that the rod is not higher elevated.

In order to retain the rod in such elevated position and keep the circuit closed, a holding latch 43 is horizontally mounted with a spring 44, to normally press against the rod. The latch so slips into a notch 45, located in the side of the rod at a point opposite the latch when the bolt is fully compressed. The rod is so held in such elevated position when the front door closes, and the light signal continued until the latch is withdrawn by the owner as follows:

On the lower portion of the mail chute I provide a door 46 for the removal of the mail. This door is preferably suspended on hinges 47, to swing outwardly from the chute and I attach to the inner side of the door near the top thereof the lower end of a cord or wire 48, and attach the other end of the cord to the outer end of a bell crank 49. The latter connected by a wire 50 to the outer end of the latch. The cord 47 is suitably guided over loose pulleys 51 and 52, and the latch is thereby withdrawn from the notch 45, and the circuit light so extinguished when the door 46 is opened.

In practice, the tip or extreme lower end of the strap 29 is slightly upturned, to provide a rounded bearing surface which will freely slide from the notches and pass over the teeth 31, as the door 21 is closed.

The complete box and chute are preferably built into the outer wall of a house, so that the

door 21 may be opened from the outside, and the lower door 46 opened inside the house. In cases where the box is built into the walls of a hallway as in an apartment house, then the lower door may be located on the same side as the upper door 21. The box may also be conveniently used as a mount for an ordinary push button for a door bell. The bell being connected at any suitable place in the house, by circuit wires 54 and 53, one of which is suitably attached to the transformer 17 for electrical operating current to ring the bell.

I have herein described and illustrated a number of old features in combination with the new features hereinafter claimed, as it is believed that the importance and convenience of the new features may be best appreciated when assembled as herein described, particularly for mail boxes for residences and apartments. My features believed new, comprise especially the form of lug used on the door, with one side toothed for providing intermittent alarms, and the other side of the same lug made smooth for elevating a shift rod for providing a continuous light signal, the smooth side of the lug formed as a cam to provide an eccentric movement, to permit the lug to continue to open after the light has been connected by the first movement of the lug; all of my features being compactly built and arranged in the upper part of the box, and positive in operation, and simple in construction, and without complicated levers which would interfere with satisfactory use of the box for the purposes intended.

Having described my invention, I claim as new 110 for Letters Patent:

In combination with a mail box having a door, an electric bell signal, an electric visual signal, independent circuits for the signals, energizing means for the circuits, a switch member for the circuit for the bell, a switch member for the circuit for the visual signal, and a single element carried by and movable with the door, said element formed with spaced projections to intermittently actuate the switch member for the bell circuit as the door is opened, said element being further provided with a cam surface to engage and operate the switch member for the visual signal into circuit-closing position as the door is opened, means for holding the last named switch member in circuit closing position following cam operation, and means for releasing the holding means at will, whereby in the opening of the door, the bell is intermittently sounded and the visual signal continuously energized.

JAMES A. CASSEL.
